(57) CLAIM

The ornamental design for a table, as shown and described.

DESCRIPTION

FIG. 1 is a side and top perspective view of the table of my design;

FIG. 2 is a side view of the table (the other side view is a mirror image of this view and is not shown);

FIG. 3 is an end view of the table (the other end view is a mirror image of this view and is not shown); and,

FIG. 4 is a top view of the table.

The bottom of the table is flat and unornamented.
